UNITED STATES PATENT OFFICE.

FRANK P. LEFFINGWELL, OF CHICAGO, ILLINOIS.

SCHEDULE OR TABLE.

No. 827,161.

Specification of Letters Patent.

Patented July 31, 1906.

Application filed October 29, 1904. Serial No. 230,466.

To all whom it may concern:

Be it known that I, FRANK P. LEFFINGWELL, a resident of Chicago, in the county of Cook and State of Illinois, have invented certain new and useful Improvements in Schedules or Tables, of which the following is a full, clear, and exact description.

The invention relates to schedules or tables—such, for example, as time-tables—and designs to provide improved means for tracing a given line from end to end thereof.

In railroad time-tables consisting of a list of many trains it has been difficult and inconvenient to trace a line containing the time of all trains stopping at a station, because some of the train-figures were located some distance from the station list or column. To make the time-table less difficult to trace, it has been customary to subdivide the table by horizontal lines or spaces and to repeat the station-list at several points between the train-figures. In practice, however, the subdivision of the table into sections or groups aided but little in referring to train-figures remotely located from a station-list, because of the uniformity of appearance of adjacent groups. When the station-list was repeated at different places, the width of the table was necessarily increased, and even then close examination was necessary to avoid error in tracing a line.

The invention designs to overcome these objections to time-tables and similar objections to schedules or tables for other purposes and to provide a schedule or table in which it is not necessary to repeat the list at several places and in which the figures alined with any point in the list can be readily, quickly, and conveniently traced from end to end.

The invention consists in the novel features hereinafter set forth, and more particularly defined by claims at the conclusion hereof.

In the drawings, Figure 1 is a plan of a time-table embodying the invention. Fig. 2 is a plan of an insurance rate-table embodying the invention.

Referring to Fig. 1 of the drawings, 1 denotes a sheet or folder having at one side thereof a column 2 wherein the stations are printed in regular order. A series of columns 3, which are arranged collaterally of each other and of the station-column 2, contain the figures for each train in vertical succession. The corresponding time of the trains is printed in horizontal alinement with the several stations in the station-column, and for clear-

ness in tracing the figures in the several columns in which the time of trains is noted the sheet is usually subdivided into sections or groups by horizontal lines 9. A series of characters 4 (such as letters or numerals) are arranged in said sections, one of such series being placed in each section, and additional characters are displayed at intervals in corresponding horizontal alinement throughout the width of the sheet, as at 5, 6, 7, and 8. Such arrangement clearly preserves an appearance of continuity of the sections and a distinction between the sections across the entire width of the time-table. Such characters are printed in contrasting color or style of letter or numeral different from the train-figures and have been in the same columns in which the figures indicating the time of the trains are shown. The marked contrast in color or style of letter clearly distinguishes the characters from the figures indicating the time of the trains, and by printing these characters in the train-columns the necessity of increasing the width of the sheet or folder is avoided. The identifying characters 4, &c., are somewhat larger than the figures in the columns 3, so these will be clearly seen and the several subdivisions will be distinguishable from each other at a glance. The sections and alined train-figures can be readily traced from the station-column without close examination. For example, if a patron is desirous of ascertaining the time of the trains stopping at Hyde Park he can easily do so by noting that said station is the second station in the section or subdivision which contains the identifying characters C at intervals throughout its width, and which section is easily distinguishable throughout its width by the large and plain identifying characters. Thus it will be seen that the patron can readily and clearly see and distinguish the alined figures of any one of the stations without closely examining and tracing all the alined figures for a particular station from that station in the station-column.

In Fig. 2 the invention is applied to an insurance rate-table having the endowment terms arranged in a list 10 and the insurance-rate for persons of different ages arranged in columns 11. The table is subdivided into horizontal sections or groups by spaces and has identifying characters 4, 5, and 6 printed in alined series and in contrasting color across each group or section.

The invention is not to be understood as

restricted to the precise arrangement shown and described, since these can be varied without departing from the spirit of the invention. The invention can be applied to advantage 5 on schedules or tables of various sorts and used for other purposes than those shown and described and is not to be understood as restricted to schedules or tables of the character shown, except where these are specifically defined in the claims.

Having thus described the invention, what I claim as new, and desire to secure by Letters Patent, is—

1. A schedule or table having printed thereon an indicating-list, a series of reference-numerals arranged in columns each column being designated by one of the members of said list and being arranged in sections or groups each embodying a plurality of said 15 columns, and distinctive characters displayed in a plurality of alined series upon said schedule or table to distinguish said sections or groups from each other, some of such characters being printed in or partially in the portions whereon the figures are printed.
2. A schedule or table having printed thereon an indicating-list, a series of reference-numerals arranged in columns each column being designated by one of the members 20 of said list and being arranged in sections or groups each embodying a plurality of said columns, and distinctive characters displayed
3. A schedule or table having printed thereon an indicating-list, a series of reference-numerals arranged in columns each column being designated by one of the members of said list and being arranged in sections or groups each embodying a plurality of said 25 columns, and distinctive characters displayed

in a plurality of alined series upon said schedule or table to distinguish said sections or groups from each other, some of such characters being printed in or partially in the portions whereon the figures are printed, said characters being in contrasting color. 35

3. A time-table having printed thereon a list of stations, the time of trains indicated in 40 horizontal columns and being arranged in horizontal sections each embodying a plurality of said columns, said sections being distinguished from each other by distinctive characters displayed in a plurality of alined 45 series across the time-table, some of such characters being printed in or partially in the portions whereon the train-figures are printed.

4. A time-table having printed thereon a list of stations, the time of trains indicated in 50 horizontal columns and being arranged in horizontal sections each embodying a plurality of said columns, said sections being distinguished from each other by distinctive characters displayed in a plurality of alined 55 series across said time-table, said characters being in contrasting color, and being printed in or partially in the portions whereon the train-figures are printed.
